UNITED STATES PATENT OFFICE.

REGINALD C. STEEPLE, OF SPOKANE, WASHINGTON, ASSIGNOR TO HUBERT J. BRAUN, OF CHICAGO, ILLINOIS.

DESIGN FOR A CANDLE HOLDER OR A SIMILAR ARTICLE.

Application filed November 15, 1924. Serial No. 11,386. Term of patent 7 years.

To all whom it may concern:

Be it known that I, REGINALD C. STEEPLE, a citizen of the United States, and a resident of the city of Spokane, in the county of Spokane and State of Washington, have invented a new, original, and ornamental Design for a Candle Holder or a Similar Article, of which the following is a specification, reference being had to the accompanying drawing, forming part thereof.

I claim:

The ornamental design for a candle holder or a similar article, as shown.

REGINALD C. STEEPLE.
